CLAIM

The ornamental design for a step can as shown and described.

DESCRIPTION

FIG. 1 is a prospective view of a step can, showing my new design;

FIG. 2 is a top plan view thereof;

FIG. 3 is a front elevation view thereof;

FIG. 4 is a right-side elevation view thereof;

FIG. 5 is a rear elevation view thereof;

FIG. 6 is a bottom view thereof;

FIG. 7 is a left-side elevation thereof; and,

FIG. 8 is an enlarged view of the encircled portion 8 in FIG. 3.

The broken lines shown in the drawings represent portions of the step can that are for illustrative purposes only and do not form a part of the claimed design.

The additional broken lines in FIGS. 3 and 8 encircling the enlarged portion details form no part of the claimed design.
